UNITED STATES PATENT OFFICE.

THEODORE GREENWALD, OF PHILADELPHIA, PENNSYLVANIA, ASSIGNOR TO
THE NATIONAL BUTTON WORKS, LIMITED, OF PENNSYLVANIA.

DESIGN FOR A BUTTON.

SPECIFICATION forming part of Design No. 24,299, dated May 14, 1895.

Application filed January 25, 1895. Serial No. 536,274. Term of patent 3½ years.

To all whom it may concern:

Be it known that I, THEODORE GREENWALD, a citizen of the United States, residing in the city and county of Philadelphia, State of Pennsylvania, have invented and produced a new and original Design for a Button, of which the following is a specification, reference being had to the accompanying drawings, forming part thereof, in which—

10 Figure 1 represents a plan view of a button embodying my design, and Fig. 2 represents a sectional view.

15 The leading feature of my design for a button, is a head having a peripheral bead, an inner bead concentric therewith, an annular face between the two beads, and a disk-like face within the inner bead, said disk being

depressed or below the surface of the annular face.

In the drawings, A designates the head of 20 a button, the same having thereon the peripheral bead B, the inner bead C concentric therewith, the annular face D between the two beads, and the disk-like face E within said bead C and below the plane of the annular 25 face D.

What I claim is—

The design for a button substantially as described and shown.

THEODORE GREENWALD.
